COOLER FOR COOLING OIL

Filed March 24, 1932

UNITED STATES PATENT OFFICE

KENNETH M. URQUHART, OF NORFOLK, VIRGINIA

COOLER FOR COOLING OIL

Application filed March 24, 1932. Serial No. 601,025.

This invention relates to coolers for cooling oil direct from a petroleum still and before the oil is passed into storage tanks, and such like service where hot fluids must be cooled or condensed. The temperature of liquid or vaporized oil, leaving the still, is often extremely high, therefore the liquid or vaporized oil must be cooled or cooled and condensed before being stored.

10 It has been common practice to employ a conventional type of tube and shell heat exchanger for cooling the oil as it leaves the still, but much difficulty has been encountered in the use of such apparatus due to the fact that scale from the cooling water would 15 form on the outside of the tubes and eventually clog the apparatus, or at least insulate the tubes against proper transfer of heat from the oil to the water. To overcome this tendency of the tubes to accumulate scale, it has been proposed to slightly 20 bow the tubes so that elongation by thermal expansion results in a relatively great deformation of the tubes, and thereby automatically 25 causes the scale deposited on the outside of the tubes to become loosened. However, the expansion and contraction method has proven inadequate, because the 30 movements of the tubes are not sufficiently violent to shake the scale loose. Furthermore 35 such automatic flexing of the tubes can only be obtained by alternately turning on and cutting off the cooling water, which of course is objectionable and expensive.

The general object of the present invention is to provide mechanical means for flexing or jarring the tubes to any desired degree without interference with the normal 40 operation of the apparatus.

The invention is illustrated by way of example in the accompanying drawing in which:

Figure 1 is a longitudinal sectional plan 45 view of the cooler;

Figure 2 is a side view of the water pipe and cooler;

Figure 3 is an end view partly broken away;

50 Figures 4, 5 and 6 are detail views of con-

nexion between the actuating lever and the tubes; and

Figure 7 is a detail of the locking member.

Referring more particularly to the drawing the cooler or heat exchanger comprises a skeleton frame 1, having a pair of side plates 2 of channel iron construction, which are suitably secured at their opposite ends to the respective headers or heads 3 and 4. 60 Braces 9 tie the side plates together intermediate their ends and strengthen the structure as a whole. The tubes 7 communicate with these heads at their opposite ends, and head 3 is subdivided into two chambers or 65 compartments 5 and 6 into which the cooled oil enters and from which the cooled oil is discharged respectively, there being in effect two batteries of tubes. The tubes and their heads are supported on beams 8, the 70 bottom side edges of the side plates 2 resting on top of the beams.

The tubes 7 are cooled by water sprayed 75 from the nozzles 10 of a water pipe 11', mounted above and in vertical alignment with the tubes. The sprayed water drops down upon the longitudinally disposed tubes and percolates therethrough, finally escaping through the open bottom of the skeleton casing or frame. Hot oil direct from the 80 still, not shown, enters chamber 5 of head 3, through opening 11, passes through the battery of tubes connected with chamber 5, thence into chamber 4 and finally back 85 through the second battery of tubes to chamber 6. The cooled oil escapes from chamber 6 through opening 12, into storage tanks, not shown.

Secured to one of the side plates 2 is a 90 bracket 13 to which is pivoted a lever 14 having a pivoted arm 15, the free end of which projects through the side plate and is loosely attached to a tube plate 16. Plate 16 is provided with perforations 17 through 95 which the tubes loosely extend, and is preferably positioned approximately midway the length of the tubes. Thus the tubes can be conveniently flexed for the purpose of cracking and splitting away any objectionable 100 accumulation of scale, by actuation of lever

14. Due to the loose connection between the free end of lever arm 15 and the tube plate 16, and also the loose fit of the tubes in the perforations of the tube plate, it is possible 5 to strike the tubes with jarring effect in addition to subjecting them to a flexing action.

In actual practice the tubes 7 are preferably initially flexed to Figure 1 dotted line position by elevating the lever 14 also to 10 dotted line position as also indicated in Figure 1. This flexing of the tubes causes the latter to be placed under considerable tension and consequently some such means as locking member 17' is necessary to secure 15 the tube against return movement. This member 17' is connected to one of the side plates 2 by an eye bolt 18 and consequently is free to be swung into and out of engagement with the lever 14. A single hook member 20 or arm 19 positioned intermediate the ends of locking member 17' is adapted to lock the tubes in their normal or originally flexed dotted line position, whereas the free end of member 17' is provided with a pair of 25 jaws 20 between which the lever 14 is received and held for the purpose of locking the tubes in reversed flexed position to that shown in Figure 1.

It frequently happens that tubes become 30 damaged and in fact completely ruptured due to vibration set up under the surging or pulsating action of liquid pumped through the tubes, or the action of the cooling fluid passing between the tubes. This objection 35 is overcome by maintaining the tubes under tension in the manner just described. Furthermore I have found that scale can be most effectively removed when deposited on the tubes while the latter are in flexed position. 40

45 Having thus described my invention what I claim as my invention is:

1. In a heat exchanger, a header, tubes 50 communicating with said header for circulating hot oil therethrough, means for cooling the tubes, and manually operable means loosely connected to said tubes for jarring said tubes to prevent accumulation of scale thereon.

2. In a heat exchanger, a header, tubes 55 communicating with said header for circulating hot oil therethrough, means for cooling the tubes, and manually operable means loosely sleeved upon said tubes for flexing and jarring said tubes to prevent accumulation of scale thereon.

3. In a heat exchanger, a skeleton frame comprising a pair of headers, side plates connected at their ends to said headers, tubes 60 communicating with said headers for circulating hot oil therethrough, means for

cooling the tubes with water, a lever connected to one of said side plates, a pivotal arm connected to said lever and loosely coupled with said tubes for flexing the tubes to and from a straight line position to prevent accumulation of scale. 70

4. In a heat exchanger, a pair of headers, tubes communicating with said headers for circulating hot oil therethrough, water cooling means for the tubes, a lever, and means pivotally connected to said lever and loosely connected to said tubes for jarring said tubes when said lever is actuated. 75

5. In a heat exchanger, a pair of headers, tubes communicating with said headers for circulating hot oil therethrough, water cooling means for the tubes, a plate having perforations substantially larger than the cross sections of said tubes sleeved upon said tubes intermediate the headers, a lever and means connected to the lever and to said plate for flexing the tubes to and from a straight line position to prevent accumulation of scale. 80

6. In a heat exchanger, a pair of headers, tubes communicating with said headers for circulating hot oil therethrough, water cooling means for the tubes, a perforated plate positioned intermediate the headers through which the tubes loosely extend, a lever and means connecting the lever and plate for jarring the tubes. 85

7. In a heat exchanger, a header, tubes communicating with said header for circulating hot oil therethrough, cooling means for the tubes, and means connected to the tubes for flexing the tubes to prevent accumulation of scale and means for locking the tubes in flexed position. 90

8. In a heat exchanger, a header, a plurality of flexed tubes communicating with said header for circulating fluid therethrough, cooling means for the flexed tubes, and manually operable means loosely connected to said tubes for reversing the direction of flexure of said tubes to and beyond a straight line position. 105

9. In a heat exchanger, a header, a plurality of flexed tubes communicating with said header for circulating fluid therethrough, cooling means for the flexed tubes, and means for reversing the direction of flexure of said tubes and means for locking the tubes in either flexed position. 110

10. In a heat exchanger, a header, tubes communicating with said header for circulating hot oil therethrough, means for cooling the tubes, and means loosely connected with said tubes for manually flexing the tubes to and from a straight line position 120 and for inducing free oscillations of said tubes to prevent accumulation of scale thereon. 125

In testimony whereof I affix my signature.

KENNETH M. URQUHART. 130
